JOHN ERICKSON, OF CHICAGO, ILLINOIS, ASSIGNOR, BY MESNE ASSIGNMENTS, TO FIRST TRUST AND SAVINGS BANK, TRUSTEE, OF CHICAGO, ILLINOIS.

SUBSCRIBER-CONTROLLED SWITCHING APPARATUS FOR TELEPHONE-EXCHANGE SYSTEMS.

1,133,373.

Specification of Letters Patent. Patented Mar. 30, 1915.

Application filed November 12, 1906. Serial No. 343,043.

To all whom it may concern:

Be it known that I, JOHN ERICKSON, a citizen of the United States of America, and resident of Chicago, Cook county, Illinois, b have invented a certain new and useful Improvement in Subscriber-Controlled Switching Apparatus for Telephone-Exchange Systems, of which the following is a specification.

10 My invention relates to automatic or semi-automatic telephone exchange systems in which the subscribers are provided with impulse-transmitting mechanisms or calling devices for controlling the operations of the 15 electrically-propelled and step-by-step-actuated switches at the exchange or central station.

In certain respects my invention is in the nature of an improvement on the system disclosed in application Serial No. 278,901. 20 In said prior application the subscriber's calling dial is adapted by its forward rotation to operate a subscriber's individual switch, and by its back rotation to then 25 operate the next or succeeding switch, such, for example, as a first-selector, and with this arrangement the initial or first vertical step of the selectors and connectors is also accomplished by the forward rotation of the dial.

30 My present invention now contemplates the operation of the subscriber's individual switch by the forward rotation of the subscriber's dial or calling device, but over the rotary side of the subscriber's line instead of 35 over the vertical side thereof, which latter is the case in said former application, whereby all selectors and connectors or other automatic switches are controlled or operated entirely by the back rotation of the subscribers' dials or calling devices, the subscribers' individual switches thus constituting the only devices which are operatively 40 responsive to the forward rotation of said dials or calling devices.

45 With such improved arrangement and mode of operation I find that better results are obtained and that greater certainty of action is insured on the part of the exchange apparatus.

50 To the foregoing and other useful ends, my invention consists in certain features of improvement and details of construction

and combinations and circuit arrangements hereinafter described and claimed.

In the accompanying drawings, Figure 1 55 is a rear elevation of the subscriber's telephone switching mechanism embodying the principles of my invention, showing the casing removed. Fig. 2 is a similar elevation showing a number of the parts removed to 60 more clearly illustrate the impulse-transmitting means, and in this figure the rear plate is not shown. Fig. 3 is a perspective view of the so-called impulse springs. Fig. 4 shows the relation of the impulse springs 65 and the controlling impulse wheel in normal position. Figs. 5, 6 and 7 show the relative positions of the parts in Fig. 4 when the dial is carried forward. Figs. 8 and 9 show the relative positions of the same parts 70 as the dial returns to normal position. Fig. 10 is a diagrammatic view showing in a simple manner the relation of the most essential parts in the telephone and the connecting circuits with the line conductors. Fig. 75 11 is a diagram showing an established connection from the calling subscriber's station through an individual switch and a first-selector and a connector to the called subscriber's line. Fig. 12 is a plan view of a 80 line switch, showing the relative position of the different magnets.

In detail the subscriber mechanism or so-called keyboard comprises two parallel and similar plates 2 held together by suitable tie-rods 3 capped with screws 4. Peripherally, and through the center of said plates 2, there passes a shaft 5 suitably journaled and adapted to rotate. At the outer end of said shaft there is rigidly secured a dial 6 with a suitable number of finger-holes 7, properly numbered, by means of which the subscriber is guided in sending the proper number of impulses over the line. Rigidly connected to the shaft bar 85 there is a locking dog 8 which, in combination with the locking cam 9 that is suitably pivoted to the rearmost one of the parallel plates 2, furnishes the means for locking the dial 6 when the telephone is in normal 90 position—that is, when the receiver 10, shown in Fig. 10, is placed on the switch-hook 11. The switch-hook carries a cam 100 12 (Fig. 1), which latter is provided with

2
a finger 13 upon the extremity of which there is a laterally projecting insulating member 14 which, when the switch-hook is raised, engages the thumb-like section 15 of the locking cam 9, retaining said cam raised beyond the reach of the screw 16 of the locking dog 8, which screw projects to the rear so that the dial may be freely rotated while the switch-hook is up. When the switch-hook is down the insulating member 14 is, of course, withdrawn from the locking cam 9, the front part of which latter falls within the radius of the rotation of the screw 16 for preventing rotation of the dial, as already explained. It will be noticed that the locking cam 9, furthermore, is provided with an insulating cap 17 that works in conjunction with the so-called ground spring 18, retaining the latter at certain times away from the ground post 19. As soon as the dial is rotated, however, the screw 16, which passes under the locking cam 9, strikes the heel 20 of the latter, driving the insulating member 17 to the rear 25 of the angled section 21 of the ground spring 18, permitting the latter to engage the ground spring 19, thus establishing the ground spring circuit. But when the receiver is restored to the hook, as shown in Fig. 10, the insulating member 14 passes into engagement with the ground spring 18, driving the latter outwardly sufficiently to permit the tip 17 of the locking cam 9 to clear the angled section 21, at which time 30 the locking cam 9 falls into its normal locking position. The cam 12 is further provided with members 22 and 23, the former for controlling the release springs 24, 25 and 26, and the latter for controlling the ringer circuit spring 27 as well as the primary circuit springs 29 and 30 and the secondary circuit springs 28 and 28'.

It will be noticed that the locking cam 9 is provided with a restoring spring 30' 45 which insures the drop of the said cam to normal position when the switch-hook is depressed. The switch-hook proper is made up of two sections *a* and *b*, the former being insulated from the latter to prevent the subscriber from being electrically shocked upon handling the section *a*. Both sections are suitably connected by screws or securing means 31. The section *b* is bifurcated, the prong 32 being pivoted at 33 to the front frame plate of the mechanism or so-called keyboard, and the prong 34 being pivoted at 33 to the back plate of said keyboard. The prong 32 extends rearwardly, as shown in Figs. 1 and 2, and is provided at its terminal with a ratchet 35 controlled by a retracting spring 36, which ratchet is adapted to engage the ratchet-wheel 37 whenever the switch-hook is pulled down. Normally the said ratchet 35 is retained out of engagement with the said ratchet-wheel 37 by

a rest 38; but as the switch-hook begins to descend the prong 32 rises, and the under edge of the lateral member 35 of the ratchet engages the teeth of the ratchet-wheel 37, rotating the latter. This ratchet-wheel, as 70 more clearly shown in Fig. 2, is in gear with a shaft 39, to which latter is secured the governor 40 for regulating the speed of the gear 37, and for regulating the downward movement of the switch-hook 11, in order 75 to insure a contact of sufficient duration of the release springs 24, 25 and 26. The said gear-wheel 37 is loosely carried on the shaft 5, and is also adapted to be engaged by a second and similar ratchet 41 carried on the 80 so-called impulse wheel 42, which latter is rigidly secured to the shaft 5. The said impulse-wheel is equipped with a set of so-called impulse teeth 43 which, as shown in Figs. 4, 5, 6, 7, 8 and 9, are arranged 85 obliquely on the periphery of said wheel. Secured to the side of said impulse wheel and insulated therefrom is also a rotary impulse tooth 44, the radial edges of which are bent outwardly, as shown in Figs. 4, 5, 90 6, 7, 8 and 9. Said teeth are used for successively operating the impulse springs. The ratchet 41 is provided with a suitable coiled spring 45 which normally retains the said ratchet in engagement with the ratchet-wheel 37. Said ratchet is so designed that when the dial is rotated in a counter-clockwise direction (when viewed from the rear, as in Fig. 1), the ratchet 41 does not lock with the ratchet-wheel, but upon returning 100 in a clockwise direction (viewed from the rear) the ratchet is drawn closer into engagement with the ratchet-wheel 37, whereby the speed of backward rotation of the dial is controlled by the governor 40. 105

The prong 32 of the switch-hook member *b*, in addition to the ratchet 35, carries pivotally secured thereto a link member 46, the outer end of which link is curved and adapted to engage a retracting spring 47, which 110 causes a downward swing of the switch-hook about the pivots 33 when the receiver is removed. Said spring 47, as shown, is held in position by the brace 48 and the tie-rod 3. The impulse springs 49 and 50 (Fig. 115 3)—the former being known as the vertical impulse spring and the latter as the rotary impulse spring—are mounted on the back keyboard plate 2, but suitably insulated from each other and from the said plate. 120 The vertical impulse spring 49 is provided with an oblique projection or lug 51 on the under side with which the vertical impulse teeth 43 are adapted to engage for driving the spring 49 intermittently onto the ground post 19. The rotary impulse spring 50 is provided with somewhat similar mechanism for driving the said rotary spring onto the ground post once when the dial is rotated in one direction and once when rotated in the 125 130

opposite direction. The said rotary impulse spring 50 has on its under side a V-shaped member 52 having two sides *c* and *d*, and there is, in addition, an auxiliary spring 53 which works in conjunction with said V-shaped member. As shown more clearly in Fig. 3, the auxiliary spring 53 is provided with a lower curved part *e* having the rear section 54 curving outwardly, as shown also in Figs. 4, 5, 6, 7, 8 and 9. The front section 55 of said member *e* is designed to fall just below the apex of the V-shaped member 52, so that the rotary impulse tooth 44, when moved in the direction of the arrow (Fig. 4), will pass onto the curved member *e*, thus pressing the rotary impulse spring 50 onto the ground post 19 for a comparatively long time, and sending to the line a comparatively long impulse, as shown in Fig. 5. As the impulse-wheel advances, the vertical impulse teeth 43 approach the lug 51 of the vertical impulse spring 49 (Fig. 5), and eventually the first tooth *f* that meets the lug 51 clears the said lug, as shown in Fig. 6, but not until after the rotary impulse tooth 44 clears the curved member *e*. As the impulse-wheel continues to advance in the direction of the arrow (Fig. 6) the next impulse tooth will clear the projection 51, as shown in Fig. 7. Then when the impulse-wheel is released, the vertical impulse spring 49 is twice carried into engagement with the ground post 19, in the manner indicated in Fig. 8; but as the impulse-wheel nears its normal position the rotary impulse tooth 44 passes under the curved member *e* of the auxiliary spring 53 (Fig. 9), engaging the V-shaped member 52 directly and for a short time only, sending the ordinary impulse through the medium of the rotary impulse spring 50 to the line, after which the said member 52 is cleared, as shown in Fig. 4, as the impulse-wheel reaches its normal position. The operations as thus described are repeated each time that the dial is operated, and the number of impulses produced through the medium of the vertical impulse spring 49 being accurately and definitely determined at each operation of the dial by the finger-hole which the subscriber selects on the dial 6. It should be stated that a suitable stop is, of course, provided, as is well known in the art, to always limit the rotation of the dial, which stop indicates to the subscriber when he should release the dial. By referring to Fig. 10 it will be noticed that the impulse springs 49 and 50 are electrically connected with the vertical and rotary line conductors 56 and 57 that lead to the central office. The impulses may be used for operating any desirable switching apparatus. It will further be noticed that the ground spring 18, which is controlled by the cam finger 13 and by the locking cam 9, is connected directly to the substation ground G'

which is, of course, connected with one of the terminals of the central office battery B', the other terminal of which battery is connected through suitable relays or coils with the line conductors 56 and 57.

Referring to Fig. 10 it will be seen that when the switch-hook is down the ringer 58 is bridged across the line, since the springs 27 and 28 are kept in electrical connection by the arm 23 and conductor 23^a. It will also be observed that the transmitter circuit is normally open, since the springs 29 and 30 are kept apart by the arm 23. When the switch-hook goes up the ringer 58 is, of course, disconnected from the line, and the receiver 10 is connected across the line in series with the secondary winding 62 of the induction-coil 61, the primary winding 60 of which is connected in a local circuit with the transmitter 59. Since the release spring 24 is connected with the ground post 19, after the dial has been operated the pressing together of the springs 24, 25 and 26 will ground the line conductors simultaneously for the purpose of accomplishing desired restoring operations.

My improved substation apparatus may be used in connection with a telephone system in which selectors of the general type disclosed in United States Letters Patent No. 815,321, issued March 13, 1906, to Keith, Erickson and Erickson, are used, and in which connectors of the general type disclosed in United States Patent No. 815,176, issued March 13, 1906, to Keith, Erickson and Erickson, are used. Such an exchange is outlined in Fig. 11 where C represents the said selector switch and E the said connector switch. The subscriber's station is shown terminating in a switch A individual to the line and ordinarily known as a line switch. With the arrangement shown, there will, of course, be one line switch to each subscriber's line. The selectors, however, as well as the connectors, are less in number than the individual switches, and any percentage basis may be used. For example, and as is very commonly the case in exchanges, to every one hundred lines there will be provided, in addition to the regular line switches, about ten selectors and about ten connectors. In a one thousand line exchange, for example, there will be one thousand line switches and one hundred first-selectors and one hundred connectors, the connectors, of course, being arranged in groups, one for each hundred subscribers; all subscribers' lines of a certain hundred terminating, of course, in multiple bank contacts of the connectors of that particular group, as is well known. Should the exchange be equipped for a greater number of subscribers, then it becomes necessary, of course, to interpose other selectors between the first-selectors and the connectors. It

may be desirable to further insert selectors between the said last-named selectors and the connectors, said selectors being usually known as second-selectors and third-selectors. As shown in Fig. 11, the calling subscriber employs only an individual switch, a first-selector and a connector in obtaining the desired connection with the called subscriber's line. In any event, however, the individual switch, it will be seen, is the only switch or machine which operatively responds to the forward rotation of the calling dial, inasmuch as all other switches are provided with means for preventing them from operatively responding to such forward rotation. The first-selector, for example, responds to the back rotation of the dial, but the connector or other succeeding switch is then locked against operative response to the next forward rotation of the dial and only responds operatively to the vertical and rotary impulses transmitted by the back rotation of the dial after it is released by the calling subscriber.

In Fig. 11 the subscriber's individual switch A is of the general type disclosed in application Serial No. 311,327, filed April 12, 1906, in which application the individual switch is operated by a rotary impulse transmitted over the rotary side of the line by the switch-hook. It has also been proposed, in a system employing a separate impulse-transmitting key for each side of the subscriber's line, to employ the key on the rotary side of the line for transmitting a preliminary impulse over the rotary line conductor to operate the individual switch. It will be seen, however, that I am the first to provide an operative arrangement by which the individual switch is operated by an impulse transmitted over the so-called rotary side of the line when the dial is given its initial or forward rotation. Among other things I am the first to provide a dial with mechanism which will transmit a relatively long impulse upon the forward rotation thereof and a relatively short impulse over the same side of the line upon the back or return rotation of the same. Such relatively long impulse transmitted by the forward rotation of the dial tends to insure the proper operation of the individual switch. For the final rotary impulse transmitted by the final return or restoring movement of the dial, a comparatively short closing of the grounded circuit is sufficient, inasmuch as the subscriber releases the dial and allows it to return of its own accord to normal position. In operating the individual switch, however, the calling subscriber might rotate the dial very quickly, and in such case a short contact arrangement might not be sufficient, and the switch would then fail to operate. Consequently, with my improved arrangement by which a sufficient closing of

the grounded circuit is insured upon the forward rotation of the dial, even though the rotating of the dial be done quickly, the proper responsive action of the individual switch is insured.

The back rotation of the dial is governed or controlled, so that in this case only a comparatively short or momentary contact arrangement is necessary in order to insure the proper energizing of the rotary line relays of the selectors and connectors. For example, in Fig. 11 of the drawings the trunk line B connects the individual switch with the selector C, and a second trunk line D leads from the said selector to the connector E. As previously stated, this connector will not respond to the forward rotation of the dial, when the latter is operated for the last two digits of the called number. The so-called rotary relay and private magnet of the connector will be energized by such forward rotation of the dial. Inasmuch as the mechanism of the connector side switch is at such time locked in first position, such energizing of the private magnet will not release the side switch and will not produce any undesirable results. After the connector has been operated by the so-called vertical impulses transmitted by the back rotation of the dial, the said private magnet is, of course, then in condition to respond operatively to the single so-called rotary impulse transmitted by the final restoring movement of the dial, permitting the side switch to shift to second position. The next forward rotation of the dial will not operate the connector side switch, because the latter is then locked in second position by the cam on the shaft of the connector. The dial when released for the last time will then accomplish the final operations of the connector in the usual manner. As the said connectors as well as the selectors are well known and understood, it will not be necessary to describe them in detail. It may be stated, however, that when second and third selectors are employed they do not operatively respond to the forward rotation of the calling dials, for substantially the same reason that the connectors do not operatively respond to such forward rotation. As shown, the system is operated on the local battery plan, but it will be understood, of course, that common battery connectors and subscribers' telephones can be employed if necessary or desirable. It will also be understood that in the drawings the calling dial mechanism is shown reversed—that is to say, in such manner that it is viewed from the back. Ordinarily, however, the subscriber's switch-hook projects to the left, so that the finger-holes in the calling dial are in position to be engaged by the right hand of the calling subscriber.

With an elongated or prolonged prelimi-

nary impulse, such as the one transmitted by the forward rotation of the subscriber's calling dial, the ground circuit is liable to remain closed after the individual switch is operated, and such preliminary impulse then has access to the next switch, such, for example, as the first-selector. For reasons already explained, however, the first-selector cannot operatively respond to such preliminary impulse over the rotary side of the line circuit, because its side switch is locked in first position.

The line or individual switch, as shown in Fig. 12, is built about a metallic base or frame 63, and comprises a plunger 64 and plunger-arm 65. It is also equipped with a bridge-cut-off relay 66, a trip magnet 67 and switch release magnet 68. A section of the metal from the central portion of the frame 20 is removed to make the structure as light as possible, while another section of the portion is turned up at right angles to the base of the frame to form a lug or flange 69 upon which the said switch release magnet is 25 mounted. Said flange has stamped through it a couple of circular holes through which the ends of the cores 70 are passed to maintain the coils of the said release magnet parallel with the base of the frame. They are 30 retained in this position by a U-shaped locking collar 71, between the faces of which the magnet supporting flange 69 extends, and which collar has four openings, two on each of the parallel faces, arranged to form two 35 tandem sets through which the cores 70 of the switch release magnet pass, as shown. After the coils of the magnet are inserted in position, the cores are then tightened in place by a shearing action produced upon 40 the said cores of the switch release magnet between the flange and the capping collar by means of a screw 72 that passes through a threaded portion on the said collar, the end of which screw is forced onto the upper 45 edge of the magnet-supporting flange 69. The said switch release magnet is provided with an armature 73 that is pivoted on a pin 74 which rises from the base of the switch. The said armature carries, pivotally secured 50 on its end, a second armature 75 that is controlled by the trip magnet 67. The pin 76 about which the armature 75 oscillates is carried on the end of the armature 73. The plunger 64 is pivotally secured by the pin 77 55 to the plunger arm 65, which latter is in turn pivoted to a pin 78 that rises from the switch frame 63. The lug 79 is stamped out of the frame 63 and is provided as a stop or rest for the armature 73. The trip magnet 67 is mounted upon the frame 63 in the same manner as the release magnet 68. Upon the armature 75 is secured the catch 80 which is adapted to engage the end 81 of the plunger arm 65.

65 The general operation of the switch is as

follows: The trip magnet 67 is energized by the preliminary impulse and the armature 75 is attracted against the magnet cores. When the armature 75 is attracted to the left (Fig. 12) the catch 80 slides out of contact with the end 81 of the plunger arm 65, and the said plunger arm 65, due to the tension of the spring 82, moves about the pin 78 and thrusts the plunger 64 into the bank terminal J. When the trip magnet again deenergizes, the trip armature 75 falls against the end of the plunger arm 65, but out of engagement therewith. The switch is restored when the release magnet 68 becomes energized, whereby the armature 73 is attracted, and accordingly the connected trip armature 75 is moved upwardly until the catch 80 passes over the end 81; then when the release magnet 68 becomes deenergized the armature 73 returns to normal 75 position, at rest against the stop 79. Furthermore, since the plunger arm 65 is now in engagement with the armature 75, the said plunger arm is also moved about the pin 78, whereby the plunger 64 is removed 80 from the bank J to the position shown, in engagement with the plunger shaft 83.

The master switch, which is shown diagrammatically below the individual switch A and the first-selector C, may be of any 95 suitable or approved type, and is provided for operating the plunger shaft 83 and for controlling certain circuits that will be disclosed hereinafter. Said master switch comprises, among other details, a motor magnet 84 for 100 operating the ratchet-wheel 85, said ratchet-wheel being provided with a number of pins 90, 91, 92 and 93 through the medium of which, and by the cooperation of the cam 89, the plunger shaft 83 is operated. It will be noticed that rigidly connected to the said cam 89 there is a master switch wiper 88 which is maintained in contact with the master switch bank O. Said master switch bank O comprises a set of contacts & arranged along the arc of a circle and a common member 87. The arrangement is such that the wiper 88 is adapted to maintain at all times some one of the contacts & in electric connection with the common segment 110 87. Furthermore, and referring to the bank J of the individual switch (Fig. 12), it will be understood that the bank J comprises a series of sets of springs similar to the springs 111, 112, 113, 114, 115, 116, 117 and 118 arranged along the segment of the circle and corresponding to the different positions of the individual switch plunger 64. It may be assumed that when the individual switch plunger 64 is in the first position it 120 is opposite the said springs shown in Fig. 12. Of course, when the plunger passes to second position it will be carried opposite a similar and adjacent set, and when it passes to third position it will be opposite a third 125 130

6
 set, etc. The arrangement in this system is such that when the master switch wiper 88 is in first position—that is, when the master switch wiper 88 is on the contact point 97—5 the individual switch plunger 64 is then retained by the plunger shaft 83 opposite the first set of bank springs 111, 112, 113, 114, 115, 116, 117 and 118; and when the motor magnet 84 energizes and advances the 10 ratchet wheel 85 one step, the pin 90, through the medium of the cam 89, advances the master switch wiper 88 onto the second master switch bank contact 102, and at the 15 same time it advances all idle individual switch plungers opposite the second set of individual bank springs, and so on for ten successive steps of the ratchet wheel 85. After the wiper has been carried onto the tenth contact, then when the motor magnet 20 energizes again the pin 90 on the ratchet wheel 85 nears the end of the cam 89, and the retracting spring 96 restores the master switch wiper 88 and the plunger shaft 83 to the first position. At each position it is 25 brought to a standstill by the engagement of the cam 89 with the succeeding pin 91. It will be seen, therefore, that the continued operation of the motor magnet 84 produces an oscillatory movement of the master 30 switch bank wiper and of the plunger shaft 83. In addition, the master switch is provided with a differential relay 86 comprising two windings, which windings are in opposition across the terminals of the battery B'. The said differential relay has 35 allotted to its control a couple of springs 100 and 101 comprising the energizing circuit of the motor magnet 84, and whenever said differential relay energizes, the said 40 springs 100 and 101 are carried into contact for operating the said motor magnet. The master switch has, in addition, an auxiliary relay 119 for controlling the energizing circuits of all trip magnets 67 of the individual 45 switches controlled by the master switch. The said relay is included in the circuit that extends between the common segment 87 of the master switch bank O and the two windings 120 and 121 of the differential 50 relay 86. Therefore, whenever the differential relay 86 is energized, the auxiliary relay 119 energizes also, making it impossible for any trip magnet to be operated while the master switch is in operation. 55 The first-selector C is of the general type disclosed in said United States Letters Patent No. 815,321. The only difference between the said selector C and that of said patent is that the line relays 103 and 104 60 are connected directly to the battery B', and not through the bridge-cut-off relay springs, as shown in the said patent. Therefore, the bridge-cut-off relay springs and the bridge-cut-off relay are dispensed with. 65 Furthermore, the vertical, rotary and pri-

vate normal conductors are disconnected from the selector and are allotted to the individual switch A. In the drawings (Fig. 11) the mechanism of the switches is not shown, but the circuits are outlined, which 70 circuits comprise and are controlled by the line relays 103 and 104, the vertical magnet 122 for raising the shaft, the private magnet 123 for controlling the side switch, the rotary magnet 124 for rotating the 75 switch-shaft, the release magnet 125 for restoring the switch after it has been used, and the release relay 126 through the medium of which the release magnet 125 is energized after the connection has been established to some other switch, such as the connector E. The side switch wipers are indicated at 106, 107, 127 and 128. The shaft wipers are indicated at 128, 129 and 130. 80

85 The connector E is of the general type disclosed in said United States Patent No. 815,176, and, as is well known, comprises the line relays 112^a and 113^a, the vertical magnet 129', the rotary magnet 130'; the 90 private magnet 131, the release magnet 132, the vertical back-bridge relay 133 and the rotary back-bridge relay 134, and the ringer relay 135. Of course, the said vertical magnet controls the vertical operation of 95 the switch-shaft that carries the line and private wipers 136, 137 and 138. The rotary magnet 130' controls the rotation of the switch-shaft. The private magnet 131 controls the side switch; the ringer relay 135 100 controls the signaling, and the release magnet 132 controls the releasing of the switch. The back-bridge relays 133 and 134 comprise means under the control of the called subscriber for releasing the connector if 105 he should so desire. The side switch, as shown, comprises the side switch wipers 139, 140, 141 and 142.

110 As shown in Fig. 11, suppose that the subscriber at substation #500 desires to call the substation #220; then when the dial is given its first forward rotation the rotary impulse tooth 44 engages the rotary impulse spring 50, as previously explained; and as shown in Fig. 5, preliminary ground 115 impulse is sent over the rotary line conductor 57, whereby the trip magnet 67 of the line switch A becomes energized over the following path: from ground G' through the coöperating ground springs 18 and 19, rotary impulse spring 50 to the rotary line conductor 57, bridge-cut-off springs 108 and 109 through the winding of the trip magnet 67, springs 110 and 111 of the master switch relay to the battery lead 105, thence through 120 battery B' and to ground G'. The trip magnet 67 upon energizing attracts its armature 75, thus drawing the catch 80 from the terminal 81 of the plunger arm itself, whereby the plunger 64 by the force 125 130

of the spring 82 is thrust onto the plunger bank terminal J, assuming that the plunger is in first position. When the plunger enters the bank the springs 111 and 114 are carried into contact, and the springs 115 and 118 are carried into contact, whereby the subscriber's line conductors 56 and 57 are extended to the trunk conductors B which lead to the first-selector C. Furthermore, the springs 116 and 117 are carried into contact, and the release magnet 68 of the individual switch A is placed in connection with the third or trunk-release conductor 143 that terminates in the release relay spring 144 at the selector C, controlled by the release relay 126. Furthermore, the bank springs 112 and 113 are carried into contact, whereby the guarding potential is established at the connector bank contacts of the calling line, and whereby the circuit is established through a cut-off relay 66 for disconnecting the trip magnet 67 from the rotary line conductor 57. The first digit being 2, the grounding of the vertical and rotary line conductors 56 and 57, when the calling subscriber operates his dial, energizes the vertical and rotary line relays 103 and 104 of the first-selector C, whereby the said selector operates, as is well known, to extend the conductors leading to it to the trunk conductors D, which latter in this case lead to the connector E.

The grounding of the line conductors 56 and 57 for the last two digits has the result of operating the connector E to establish connection with the line #220. If the said line is not busy the said operations are performed through the medium of the vertical and rotary line relays 112^a and 113^a. After the central office switches have been operated, as described, they may be restored to normal condition by the calling subscriber upon hanging up his receiver, at which time, as is well known, the vertical and rotary line conductors 56 and 57 are, of course, simultaneously grounded, when the release springs 24, 25 and 26 are pressed into contact. Of course, the line relays 112^a and 113^a are energized simultaneously, at which time the trunk-release springs 140' and 141' are carried into engagement, and the trunk-release circuit is established that comprises the release magnet 132 of the connector E; and the back-release relay 126, upon pressing the spring 144 upon the ground spring 145, closes a second energizing circuit through the release magnet 68 of the individual switch A and a multiple circuit through the release magnet 125 of the selector C. When the release magnet of the connector is energized, the connector switch-shaft and side switch are restored to normal position; but the selector C and individual switch A are not released until the substation ground is broken, when the release springs 24, 25 and

26 separate, at which time the central office switching apparatus is fully and finally restored.

What I claim as my invention is:

1. In a telephone exchange system, the combination of a subscriber's rotatable calling dial, an impulse-transmitting mechanism governed thereby, an automatic switch responsive to the operation of said mechanism by the forward rotation of said dial, when rotated for the first digit, another switch responsive to the operation of said mechanism by the return or backward rotation of the dial, a third switch responsive to the backward rotation of the dial when rotated for the second digit, and means for preventing said third switch from operatively responding to the forward rotation of the dial.

2. In a telephone exchange system, the combination of a subscriber's rotatable calling dial, a subscriber's individual switch, a first-selector switch, a subscriber's telephone line, means by which the forward rotation of the dial transmits an electrical impulse over one side of the line to operate the said individual switch, and means by which the backward rotation of the dial transmits one or more electrical impulses over the line to both initially and finally operate the selector-switch.

3. In a telephone exchange system, the combination of a subscriber's calling dial, a subscriber's telephone line provided with so-called rotary and vertical line conductors, a subscriber's individual switch, another switch having vertical and rotary motion controlled over said line conductors, and means by which the forward rotation of the dial transmits a preliminary electrical impulse over the rotary side of said line to operate the said individual switch.

4. In a telephone exchange system, the combination of a subscriber's calling dial, a subscriber's telephone line, means by which the forward rotation of the dial transmits an electrical impulse over one side of said line, and means by which the backward rotation of said dial transmits electrical impulses over both sides of said line, together with switching apparatus operatively affected by said impulses.

5. In a telephone exchange system, the combination of a subscriber's rotatable calling dial, a subscriber's telephone line, means by which the forward rotation of the dial, when rotated for the first digit, transmits a relatively long electrical impulse over one side of the line, and means by which the backward rotation of the dial transmits one or more electrical impulses of shorter duration over the other side of the line, followed by an impulse over the first side of the line, together with switching apparatus operatively affected by said impulses.

6. In a telephone exchange system, the combination of a subscriber's rotatable dial, a subscriber's telephone line, means for grounding the so-called rotary side of the line upon both the forward and back rotation of the dial, and means for grounding the so-called vertical side of the line upon the backward rotation of the dial, together with automatic switches responsive to such 10 grounding of the line.
7. A telephone exchange system comprising a subscriber's rotatable dial, a subscriber's telephone line, means by which one side of the line is grounded on both the forward and backward rotation of the dial, and means by which the other side of the line is grounded upon the back rotation of the dial, together with automatic switching means responsive to such grounding of the line. 15
8. In a telephone exchange system, the combination of a subscriber's movable calling device, a subscriber's telephone line, means by which the forward movement of said device operates to ground one side of the line, means by which the return or backward rotation of the dial operates to ground both sides of the line, one side at a time, together with automatic switches responsive to such grounding of the line. 20
9. In a telephone system, a subscriber's line, a non-numerical trunking switch individual thereto, a connector for finding the called line, means including a selector for trunking the individual switch into connection with the said connector, a subscriber's calling mechanism provided with a rotary dial, means whereby the forward rotation of said dial operates the said non-numerical individual switch, and means whereby the 25 backward rotation of the dial is operative to control the selector and the connector. 30
10. In a telephone system, a connector having one motion to select groups and another motion to find the called line in any selected group, means including a subscriber's non-numerical individual trunking switch for extending connection to said connector, a subscriber's calling mechanism provided with a rotary dial, means whereby the said non-numerical switch is responsive to the forward rotation of said dial, and means whereby the said connector is responsive to the backward rotation of said dial. 35
11. In a telephone system, an automatic numerical trunking switch having one motion to select groups and another motion to automatically find an idle trunk in any selected group, a non-numerical trunking switch, a calling mechanism provided with a rotary dial, means whereby the non-numerical trunking switch is responsive to the forward rotation of said dial, and means whereby the said numerical switch is responsive to the backward rotation of said 40 dial. 45
12. In a telephone system, the combination of a subscriber's rotary calling dial, a subscriber's telephone line, means by which the initial forward rotation of said dial transmits a relatively long electrical impulse over one side of the line, means by which the backward rotation of the dial transmits one or more electrical impulses of shorter duration over the other side of the line, followed by a single impulse over the 50 first-mentioned side of the line of short duration, and switching apparatus controlled by said impulses. 70
13. In a telephone exchange system, the combination of a subscriber's reciprocating calling dial, an impulse transmitting mechanism governed thereby, an automatic switch responsive to the operation of said mechanism by the forward motion of said dial, when operated for the first digit, another switch responsive to the operation of said mechanism by the return or backward motion of the dial, a third switch responsive to the backward motion of the dial when operated for the second digit, and a latch for preventing said third switch from operatively responding to the forward rotation of the dial. 80
14. In a telephone exchange system, the combination of a subscriber's reciprocating calling dial, a subscriber's individual switch, a first-selector switch, a subscriber's telephone line, an impulse sender controlled by the dial by which the forward rotation of the dial transmits an electrical impulse over 85 one side of the line to operate the said individual switch, and by which the backward rotation of the dial transmits one or more electrical impulses over the line to both initially and finally operate the selector 90 switch. 100
15. In a telephone exchange system, the combination of a subscriber's calling dial, a subscriber's telephone line provided with so-called rotary and vertical line conductors, a subscriber's individual switch, another switch having vertical and rotary motion controlled over said line conductors, and an impulse sender controlled by the dial by which the forward rotation of the dial transmits a preliminary electrical impulse 105 over the rotary side of said line to operate the said individual switch. 110
16. In a telephone exchange system, the combination of a subscriber's calling dial, a subscriber's telephone line, an impulse sender controlled by the dial by which the forward rotation of the dial transmits an electrical impulse over one side of said line, and by which the backward rotation of 115 said dial transmits electrical impulses over both sides of said line, together with switching apparatus operatively affected by said impulses. 120
17. In a telephone exchange system, the 125

combination of a subscriber's rotatable calling dial, a subscriber's telephone line, an impulse sender controlled by the dial by which the forward rotation of the dial when 5 rotated for the first digit, transmits a relatively long electrical impulse over one side of the line, and means by which the backward rotation of the dial transmits one or more electrical impulses of shorter duration 10 over the other side of the line, followed by an impulse over the first side of the line, together with switching apparatus operatively affected by said impulses.

18. In a telephone exchange system, the 15 combination of a subscriber's rotatable dial, a subscriber's telephone line, an impulse sender controlled by the dial for grounding the so-called rotary side of the line upon both the forward and back rotation of the 20 dial, and for grounding the so-called vertical side of the line upon the backward rotation of the dial, together with automatic switches responsive to such grounding of the line.

25 19. A telephone exchange system comprising a subscriber's rotatable dial, a subscriber's telephone line, an impulse sender controlled by the dial by which one side of the line is grounded on both the forward 30 and backward rotation of the dial, and by which the other side of the line is grounded upon the back rotation of the dial, together with automatic switching means responsive to such grounding of the line.

35 20. In a telephone exchange system, the combination of a subscriber's movable calling device, a subscriber's telephone line, an impulse sender controlled by the dial by which the forward movement of said device 40 operates to ground one side of the line, and by which the return or backward rotation of the dial operates to ground both sides of the line, one side at a time, together with automatic switches responsive to such grounding 45 of the line.

21. In a telephone system, a subscriber's line, a non-numerical trunking switch individual thereto, a connector for finding the called line, a progressively movable trunk- 50 ing switch for trunking the individual switch into connection with the said connector, a subscriber's calling mechanism provided with a rotary dial, an impulse

sender controlled by the dial which upon the forward rotation of said dial operates the 55 said non-numerical individual switch, and which upon the backward rotation of the dial is operative to control the selector and the connector.

22. In a telephone system, a connector 60 having one motion to select groups and another motion to find the called line in any selected group, a subscriber's non-numerical individual trunking switch for extending connection to said connector, a subscriber's 65 calling mechanism provided with a rotary dial, an impulse sender controlled by the dial, said non-numerical switch responsive to said sender upon the forward rotation of said dial, and the said connector is responsive also to said sender upon the backward rotation of the dial.

23. In a telephone system, an automatic numerical trunking switch having one motion to select groups and another motion to 75 automatically find an idle trunk in any selected group, a non-numerical trunking switch, a calling mechanism provided with a rotary dial, an impulse sender controlled by the dial, said non-numerical trunking 80 switch responsive to the sender upon the forward rotation of said dial, the said numerical switch also responsive to the sender upon the backward rotation of said dial.

24. In a telephone system, the combination of a subscriber's reciprocating calling dial, a subscriber's telephone line, an impulse sender controlled by the dial through the medium of which said dial transmits a 90 relatively long electrical impulse over one side of the line upon forward motion and through the medium of which the dial transmits one or more electrical impulses of shorter duration over the other side of the 95 line upon backward motion, followed by a single impulse over the first-mentioned side of the line of short duration, and switching apparatus controlled by said impulses.

Signed by me at Chicago, Cook county, 100 Illinois, this 7th day of November, 1906.

JOHN ERICKSON.
